COMPRESSOR UNLOADER

Burton S. Aikman, Wilkinsburg, Pa., assignor to
The Westinghouse Air Brake Company, Wil-
merding, Pa., a corporation of Pennsylvania

Application September 4, 1935, Serial No. 39,133

8 Claims. (Cl. 230—24)

This invention relates to a control system for a fluid compressor driven by an internal combustion engine.

It is the principal object of this invention to provide a control system for a fluid compressor driven by an internal combustion engine, the control system comprising unloading means associated with the compressor and operated by the vacuum in the inlet passage of the engine.

10 A further object of this invention is to provide a compressor control system of the type referred to and which incorporates means responsive to the pressure of the fluid compressed by the compressor and controlling a communication between the engine intake passage and the unloading means, whereby the unloading means is controlled by the engine intake pressure in response to variations in the pressure of the fluid compressed by the compressor.

20 Another object of this invention is to provide a compressor control system of the type referred to and which incorporates means subject to the pressure of the fluid compressed by the compressor and subject also to the vacuum in the inlet passage of the engine and controlling a passage between the engine inlet passage and the unloading means.

25 A further object of this invention is to provide a compressor control system of the type referred to and having means subject to the pressure of the fluid compressed by the compressor, said means being biased to a position to maintain the compressor loaded and being movable on a predetermined increase in the pressure of the fluid compressed by the compressor to a position to effect unloading of the compressor, said means being subject also to the vacuum in the engine inlet passage on movement to the unloading position, whereby said means is maintained in said unloading position until the pressure of the fluid compressed by the compressor is reduced to a value substantially less than that required to effect movement of the said means from the loading position to the unloading position.

40 Other objects of the invention and features of novelty will be apparent from the following description taken in connection with the accompanying drawing, the single figure of which is a diagrammatic view, partly in section, of a fluid compressor equipped with one embodiment of the control system provided by my invention.

45 Referring to the drawing a compressor is indicated generally by the reference character 1 and is driven by an internal combustion engine 3, which may be of any suitable well-known con-

struction and is provided with a fuel inlet passage or manifold 5 through which fuel is supplied to the cylinders of the engine.

The compressor 1 comprises a body having a crank case chamber 10 formed therein, and having a cylinder 11 associated therewith and provided with a bore in which is reciprocably mounted a piston 14. The upper end of the bore in the cylinder 11 is closed by means of a cylinder head 15, which has a chamber 16 formed therein, and in which is positioned an exhaust valve 18 which is urged by means of a spring 22 into engagement with a seat 19 surrounding a passage 20 communicating with the chamber above the piston 14 and with the chamber 16 in the cylinder head 15. The chamber 16 is connected with a reservoir 25 by way of a pipe 26.

The wall of the cylinder 11 has an annular passage 30 formed therein surrounding the bore in the cylinder and communicating with this bore by way of a plurality of ports 32 which extend through the wall of the cylinder and which communicate with the bore at a point just above the top of the piston 14, when the piston is at the lower end of its range of movement. A passage 35 is provided in the wall of the cylinder 11 and communicates with the crank case chamber 10 and with the passage 30.

A combined air strainer and compressor unloading device 36 is provided and controls the flow of fluid from the atmosphere to the passage 30.

The combined air strainer and unloading device 36 comprises a body section indicated generally by the reference character 38, and having a substantially cylindrical peripheral portion 39 and a central portion 40 which is connected with the peripheral portion 39 by means of a radially extending portion 41.

The central portion 40 has a valve chamber 43 formed therein in which is mounted a valve 45 having a fluted stem positioned in a bore extending through the central portion 40, and having a head adapted to seat on a seat surrounding the bore in which the fluted stem is positioned.

A pair of annular perforated members 47 and 48 are positioned in the cavity between the central portion 40 and the peripheral portion 39 of the body section 38 and have placed between them a quantity of a suitable air straining material, such as curled hair, indicated at 49. The member 48 is held in position by means of the cover plate 51, which has a projecting portion 53 formed thereon and extending within the peripheral portion 39 and engaging the member 48.

55

The cover plate 51 is held against the margin of the peripheral portion 39 of the body section 38 by means of the casing section 55 which has a threaded end portion which is screwed into threads in the wall of the valve chamber 43 in the body section 38, and which is provided with an annular flange 56 engaging the inner margin of the cover plate 51. The exposed end of the casing section 55 is threaded and is adapted to be screwed into a threaded opening in the wall of the cylinder 11, so that a passage 58 through the casing section 55 communicates with the passage 30 in the wall of the cylinder 11.

The combined air strainer and compressor unloading device 36 includes a movable abutment in the form of a diaphragm 60, clamped between the casing section 38 and a casing section 62, and having on one side thereof a chamber 64 in which is mounted a follower 65 which engages one side 20 of the diaphragm 60 and to which is secured the end of the stem of the valve 45. A spring 67 is also mounted in the chamber 64 and engages the follower 65 so as to normally urge the follower to move to the left and thus move the valve 45 25 away from its seat.

The diaphragm 60 has on the opposite side thereof a chamber 69 which is constantly connected with a chamber 70 on one side of the air straining means 49 by way of passages 72, and 30 which communicates with the valve chamber 43 by way of the bore in which the valve 45 is mounted. The chamber 74 on the opposite side of the air straining means 49 is in communication with the atmosphere by way of a passage 76. 35 The control system provided by this invention includes a control device, indicated generally by the reference character 80, and which as shown comprises a movable abutment in the form of a diaphragm 81 clamped between a casing section 40 82 and a body section 84, and having on one side thereof a chamber 86 which is constantly connected to the main reservoir 25 by way of a pipe 87. The diaphragm 81 has on the other side thereof a chamber 90 in which is positioned a 45 plunger 92.

The body section 84 has a wall 91 extending across the chamber 90 and having a passage 94 formed therein which is constantly connected with the engine inlet passage 5 by way of a 50 pipe 95. The end of the passage 94 is surrounded by a seat 96 and a ball valve 98 is held in engagement with the seat 96 by means of a spring 99 acting through a valve cage 100. The valve cage 100 is moved against the spring 99 by means of 55 the plunger 92 acting through the push pins 102, which extend through openings in the wall 91 which extends across the chamber 90.

The chamber 90 is constantly connected with the chamber 64 of the combined air strainer and 60 compressor unloading device 36 by way of a pipe 105, and is constantly connected with the atmosphere by way of a passage 106, which has a flow capacity substantially less than that of the passage 94 and pipe 95 by means of which the chamber 90 is connected to the engine inlet passage 5. 65

In the operation of the system, assuming that the compressor is idle and that the reservoir 25 is at atmospheric pressure, the spring 99 of the control device 80 will maintain the ball valve 70 75 98 in engagement with the seat 96, while the chamber 90 will be at atmospheric pressure as it is in communication with the atmosphere by way of the passage 106.

The chamber 64 of the combined air strainer and unloading device 36 will also be at atmos-

pheric pressure as it is in communication with the chamber 90 of the control device 80 by way of the pipe 105, and the spring 67 will maintain the valve 45 in the position in which it is shown in the drawing, in which position communication is permitted between the valve chamber 43 and the atmosphere through the air straining means 49. This permits fluid to be supplied to the passage 30 from the atmosphere, and effects loading of the compressor.

When the engine 3 is started the crank shaft of the compressor is rotated, and the piston 14 is caused to reciprocate in the bore in the cylinder 11. On upward movement of the piston 14 from the position in which it is shown in the drawing, 15 the piston cuts off communication through the ports 32, and on further movement of the piston the fluid in the chamber above the piston is compressed and the pressure of the fluid acting upon the exhaust valve 18 causes this valve to be 20 moved upwardly away from the seat 19 against the spring 22 so that air flows from the piston chamber to the exhaust valve chamber 16, and therefrom by way of the pipe 26 to the reservoir 25.

On downward movement of the piston 14 the exhaust valve 18 is moved into engagement with its seat 19 by the spring 22 so as to cut off the flow of fluid from the exhaust valve chamber 16 to the chamber in the bore in the cylinder 11 30 above the piston 14, with the result that a partial vacuum is created in the chamber above the piston. When the piston 14 moves to its lower position, in which position the ports 32 are again uncovered, fluid flows from the passage 30 through the ports 32 to the chamber above the piston. This produces a reduction in the pressure of the air or fluid in the passage 30 and causes air or fluid to flow to this passage from the valve chamber 43, and on a reduction in the 40 pressure of the fluid in the valve chamber 43, fluid will be supplied thereto from the atmosphere by way of the passage 76, the chamber 74, through the air straining means 49 to the chamber 70, and therefrom by way of the passages 35 72 to the chamber 69, and thence past the fluted stem of the valve 45 to the valve chamber 43.

On the next upward stroke of the piston 14 the air or fluid which is in the chamber above the piston 14 will be compressed, and this process 50 will be repeated with each revolution of the crank shaft of the compressor.

During operation of the engine 3 a partial vacuum will be established in the engine inlet passage or manifold 5, and this vacuum will be 55 communicated to the pipe 95 and the passage 94, but it will not be communicated to the chamber 90 in the control device 80 at this time as the ball valve 98 is held in engagement with the seat 96 so as to cut off communication between 60 the passage 94 and the chamber 90.

After a period of operation of the compressor the pressure of the fluid in the reservoir 25 will have increased to a predetermined value such that the pressure of the fluid in the chamber 86 65 exerts a force on the diaphragm 81 which exceeds that exerted by the spring 99, acting on the other side of the diaphragm 81 through the valve cage 100, the push pins 102, and the plunger 92. The diaphragm 81 will thereupon be forced downwardly against the spring 99, and the ball valve element 98 will be moved by gravity away from the seat 96.

As soon as the ball valve 98 moves away from the seat 96, the fluid which is in the chamber 90

will be drawn through the passage 94 and the pipe 95 to the inlet passage 5, and a partial vacuum will be established in the chamber 90, as the rate at which fluid is withdrawn from the chamber 90 through the passage 94 and the pipe 95 substantially exceeds that at which fluid is supplied to the chamber 90 from the atmosphere by way of the passage 106.

The resulting reduction in the pressure of the fluid in the chamber 90 increases the force effective to urge the plunger 92 downwardly and the plunger will thereafter be moved very rapidly until it engages the wall 91, which limits downward movement of the plunger 92.

It will be seen, therefore, that as soon as the valve 98 is moved away from the seat 96 as a result of an increase in the pressure of the fluid in the reservoir 25, it will be moved to the full open position very rapidly due to the reduction in the pressure of the fluid in the chamber 90 which occurs when the valve 98 is moved away from its seat.

On a reduction in the pressure of the fluid in the chamber 90, a similar reduction in the pressure of the fluid in the chamber 64 will be effected, as the chamber 64 is in communication with the chamber 90 by way of the pipe 105, and, on a reduction in the pressure of the fluid in the chamber 64, the diaphragm 60 will be moved to the right against the spring 67 by the pressure of the atmosphere in the chamber 68 on the opposite side of the diaphragm, and the valve 45 will be moved into engagement with the seat surrounding the passage in which the valve is mounted, thus cutting off the flow of fluid from the atmosphere to the valve chamber 43. This cuts off the supply of fluid to the compressor and causes the compressor to be unloaded, with the result that on continued operation of the compressor no fluid will be compressed by it as long as the valve 45 is in the seated position.

The compressor will continue to run in the unloaded condition until the pressure of the fluid in the reservoir 25 is reduced to a value such that the force exerted by the diaphragm 81 as a result of the fluid under pressure in the chamber 86 acting upon it, and as a result of the partial vacuum in the chamber 90 acting upon it, is less than the force exerted by the spring 99 acting through the plunger 92 and tending to move the diaphragm upwardly.

When the pressure of the fluid in the reservoir 25 has been reduced to this value the ball valve 98 will be moved into engagement with the seat 96 so as to cut off communication between the passage 94 and the chamber 90. This cuts off communication between the passage 94 and the chamber 90, and permits the chamber 90 to be restored to atmospheric pressure by the flow of fluid from the atmosphere through the passage 106. When the chamber 90 is restored to atmospheric pressure the force exerted by the diaphragm 81 acting through the plunger 92 and tending to move the valve cage 100 downwardly against the spring 99 will be decreased, with the result that the spring 99 will hold the ball valve 98 firmly in engagement with the seat 96.

When the chamber 90 is restored to atmospheric pressure a similar increase will be effected in the pressure of the fluid in the chamber 64 of the combined air strainer and unloading device 36, and the diaphragm 60 will thereupon be moved to the left by the spring 67 so that the valve 45 will be moved away from its seat to again permit the flow of fluid from the atmos-

phere to the valve chamber 43, thus effecting loading of the compressor.

The cylinder wall of the compressor is provided with a passage 35, which extends between the passage 30 and the crank case chamber 10, so that on a reduction in the pressure of the fluid in the passage 30 as result of operation of the compressor, fluid will flow from the crank case chamber 10 to the passage 30. This produces a partial vacuum in the crank case chamber 10 and causes air to tend to flow into the crank case chamber from the atmosphere through the joints in the walls of the crank case, thereby opposing the escape of lubricant from the crank case through the joints in the walls of the crank case chamber.

From the foregoing it will be seen that the compressor control system provided by this invention incorporates means responsive to the pressure of the fluid compressed by the compressor and to the pressure of the fluid in the inlet passage of the engine which drives the compressor, this means controlling the loading and unloading of the compressor.

It will be seen also that the unloading control means is responsive only to the pressure of the fluid compressed by the compressor when this pressure is below a predetermined value, and that upon an increase in this pressure to a value above said predetermined value the control means is rendered subject to the pressure of the fluid in the engine inlet passage and is operated to effect unloading of the compressor, whereby the control means is maintained in the position to effect unloading of the compressor until the pressure of the fluid compressed by the compressor falls to a value substantially lower than that originally required to effect movement of the control means to a position to effect unloading of the compressor.

This insures that there will be a pressure differential between the pressure at which the compressor is unloaded and the pressure at which the compressor is loaded. This construction also insures that when the valve means of the unloading control means is moved from the closed position to the open position, it will be moved very rapidly after the initial movement thereof away from the closed position, and that on movement of this valve means to the closed position from the open position it will be held firmly in engagement with its seat.

It will be seen also that the control device provided by this invention opens a passage through which air is supplied to the engine inlet passage when the control device moves to the position in which the compressor is unloaded. The system operates, therefore, to vary the mixture of the fluid supplied to the engine in response to the loading and unloading of the compressor, the supply of air being increased when the compressor is unloaded, at which time the load on the engine is at a minimum. As soon as the compressor is loaded, however, the supply of air to the engine inlet passage through this passage is cut off, and this has the effect of enriching the mixture of the fuel supplied to the engine when the engine is subjected to load.

While one embodiment of the control system provided by this invention has been illustrated and described in detail, it should be understood that the invention is not limited to these details of construction, and that numerous changes and modifications may be made without departing from the scope of the following claims.

Having now described my invention, what I

claim as new and desire to secure by Letters Patent, is:

- 5 1. In a control system for a fluid compressor driven by an internal combustion engine the combination of a fuel inlet passage for the engine, unloading means associated with the compressor, a control device for controlling operation of the unloading means, said control device comprising means subject to the pressure of the fluid compressed by the compressor and biased to a position to effect loading of the compressor and being moved to a position to effect unloading of the compressor on a predetermined increase in the pressure of the fluid compressed by the compressor, said means being subject to the pressure of the fluid in the engine inlet passage after movement away from the loading position, whereby the pressure required to move said means from the loading position exceeds the pressure required 10 to maintain said means away from the loading position, and whereby the compressor remains unloaded until the pressure of the fluid compressed by the compressor is reduced to a value less than that required to effect unloading of the compressor.
- 15 2. In a control system for a fluid compressor driven by an internal combustion engine, in combination, a fuel inlet passage for the engine, unloading means for the compressor, movable abutment means subject to the opposing pressures of the atmosphere and of the fluid in a chamber for controlling operation of the unloading means, means for supplying fluid to said chamber, and movable abutment means subject to the opposing pressures of the fluid in said chamber and of the fluid compressed by the compressor and controlling communication between said chamber and the engine inlet passage.
- 20 3. In a control system for a fluid compressor driven by an internal combustion engine, in combination, a fuel inlet passage for the engine, unloading means for the compressor, movable abutment means subject to the opposing pressures of the atmosphere and of the fluid in a chamber for controlling operation of the unloading means, means for supplying fluid from the atmosphere to said chamber at a given rate, and movable abutment means subject to the opposing pressures of the fluid in said chamber and of the fluid compressed by the compressor and controlling a communication between said chamber and the engine inlet passage through which fluid may flow from the chamber to the engine inlet passage at a rate more rapid than said given rate.
- 25 4. In a control system for a fluid compressor driven by an internal combustion engine, in combination, a fuel inlet passage for the engine, unloading means for the compressor, biasing means associated with the unloading means and yieldingly urging said unloading means to a position to effect loading of the compressor, movable abutment means subject to the opposing pressures of the atmosphere and of the fluid in a chamber and operated on a reduction in the pressure of the fluid in said chamber to effect movement of the unloading means to a position to unload the compressor, means for supplying fluid to said chamber, and movable abutment means subject to the opposing pressures of the fluid in said chamber and of the fluid compressed by the compressor and of the fluid in said chamber and of the fluid compressed by the compressor

and controlling communication between said chamber and the engine inlet passage.

- 5 5. In a control system for a fluid compressor driven by an internal combustion engine, in combination, a fuel inlet passage for the engine, unloading means for the compressor, biasing means associated with the unloading means and yieldingly urging said unloading means to a position to effect loading of the compressor, movable abutment means subject to the opposing pressures of the atmosphere and of the fluid in a chamber and operated on a reduction in the pressure of the fluid in said chamber to effect movement of the unloading means to a position to unload the compressor, means for supplying fluid from the atmosphere to said chamber at a given rate, and movable abutment means subject to the opposing pressures of the fluid in said chamber and of the fluid compressed by the compressor and controlling a communication between said chamber and the engine inlet passage through which fluid may flow from said chamber to the engine inlet passage at a rate more rapid than said given rate.

- 10 6. In a control system for a fluid compressor driven by an internal combustion engine, in combination, a fuel inlet passage for the engine, unloading means for the compressor, yielding means urging said unloading means to a position to effect loading of the compressor, movable abutment means subject to and operated on a reduction in the pressure of the fluid in a chamber to move the unloading means to a position to effect unloading of the compressor, means for supplying fluid to said chamber, and means responsive to the opposing pressures of the fluid compressed by the compressor and of the fluid in said chamber for establishing communication between said chamber and the fuel inlet passage.

- 15 7. In a control system for a fluid compressor driven by an internal combustion engine, in combination, a fuel inlet passage for the engine, unloading means for the compressor, a movable abutment subject to the pressure of the fluid in a chamber for operating the unloading means, means for supplying fluid to said chamber, valve means for controlling communication between said chamber and the fuel inlet passage, means responsive to the pressure of the fluid compressed by the compressor for moving said valve means to a position to establish communication between said chamber and said inlet passage, and means subject to pressure of the fluid in said chamber and opposing movement of the valve means by the means responsive to the pressure of the fluid compressed by the compressor.

- 20 8. In a control system for a fluid compressor driven by an internal combustion engine having a fuel inlet passage associated therewith, a movable abutment subject to and operated on a reduction in the pressure of the fluid in a chamber to unload the compressor, means for supplying fluid to said chamber, and a movable abutment subject to the opposing pressures of the fluid compressed by the compressor and of the fluid in said chamber and controlling a communication between said chamber and said inlet passage.
